ARTICULATED FABRIC FOR HANDBAGS

Victor Berkowitz, Lawrence, N. Y., assignor to
 Goldsmith Brothers Manufacturing Co., Inc.,
 New York, N. Y., a corporation of New York

Application December 29, 1944, Serial No. 570,236

15 Claims. (Cl. 41—10)

This invention relates to articles made of laced decorative elements.

One object of the invention is to provide a flexible fabric or handbag comprising an improved field of decorative elements in which the lacing extends in only one direction, with the decorative elements being thereby flexibly interconnected laterally of the lacing to prevent separation of the decorative elements in the direction in which they are not laced.

Another object is to provide neat, thin edge elements having lacing ears forming positioning abutments to prevent the elements from partially sliding over or telescoping each other.

Another object of the invention is to furnish such an improvement whereby all the elements are identical so that only a single mold or die is necessary, and only one kind of element need be handled in manufacturing articles of uniform contour.

Another object of the invention is the provision of improvements of the nature referred to whereby relatively few lacing members are required and each decorative element secured by at least two lacing members, each lacing member being common to two columns of the decorative elements.

Another object of the invention is to furnish improvements of the nature set forth which permits a substantial flexibility in different directions and particularly in one direction without separation of the decorative elements or "breaking" of the surface of the field of elements.

Another object of the invention is to provide a handbag having improved means of the character described whereby a high degree of flexible expansion in the thickness of the handbag is obtained without relying on the flexibility of the lacing but rather by a pivotal relation between the decorative elements and the lacing so that the latter offers no resistance and is not subject to distortion.

Another object of the invention is to provide an improved decorative plastic element having one or more of the following features: Free hinging by tape or lace receiving ears whose center lines lie in the plane of the base of the element; flexibility of a wall by tapering the element at all sides down to the base with the ears protruding partially above and below that base, thus utilizing a minimum of plastic material and obtaining a novel decorative appearance; instant interfitting of elements by placing the ears diagonally opposite corners of the element; and complete protection of the lacing from

rubbing and wear at the edges as well as at the sides of a handbag.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

15 Fig. 1 is a view in front elevation of a handbag embodying the invention, with parts of ears removed to show the lacing.

Fig. 2 is a similar view of an end of the handbag.

20 Fig. 3 is a diagrammatic horizontal view of a portion of an expanded handbag.

Fig. 4 is a full size front view of a decorative element embodying the invention.

Fig. 5 is a top edge view thereof.

25 Fig. 6 is a side edge view of the same.

Fig. 7 is a section on line 7—7 of Fig. 4.

Fig. 8 is a side edge of a modification with lacing shown in dot-dash lines.

30 The advantages of the invention as here outlined are best realized when all of its features and instrumentalities are combined, but, useful embodiments may be produced involving less than the whole.

It will be obvious to those skilled in the art 35 to which the invention appertains, that the same may be incorporated in several different constructions. The accompanying drawing, therefore, is submitted merely as showing a preferred exemplification of the invention.

40 Referring in detail to the drawing, 10 denotes an article, preferably a handbag, embodying the invention. The same may include identical side walls each having a field of decorative elements

45 11 in accordance with the invention. Those elements may consist of metal or plastic, preferably the latter. All the elements 11 are identical whereby a single mold or die suffices, and the assembling of the elements 11 is expedited.

Each element 11 comprises a main decorative 50 body or plate-like portion 12 of generally rectangular form. The same preferably includes a raised or convex section 12a extending horizontally from edge to edge of the rectangular portion, and upper and lower beveled or sloping sections 12b which meet with or intersect the convex sec-

tion. The resultant arrangement is decorative, but primarily it causes the rectangular portion 12 to have thin edges lying in a common plane, for a purpose hereinafter apparent. On the reverse side, the decorative element is hollow or concave as at 13 for lightness in weight.

Connected to the element 11 at certain opposed edges thereof, preferably at the vertical edges 14 are ears 15. The latter are desirably elongated to form tubes whose length is not more than one half the width or altitude of the decorative element 11. It is advantageous to place these ears or tubes 15 at diagonally opposite corners of the element 11, so that the elements may be interfitted without the occasional necessity of turning them around. The ears 15 thus terminate in line with the upper and lower edges 16 of the element, while their other ends terminate in the horizontal center line of the element. Both ears or tubes 15 are parallel to each other and lie with their center lines in the base defined by the edges 14 and 16 of the element. Hence the ears 15 project partly rearward and partly forward of the lines 14 and 16. Because the ears lie wholly beyond the rectangular section 12, easy register and alinement is obtained for threading the lacing 17 through the ears. It is noted that the ears form abutments preventing the thin edge elements 11 from partially telescoping or slipping over each other.

The lacing 17 forms a pintle-like means interconnecting the decorative elements in a series of rows and also interconnecting superposed rows to complete a field. Also the lacing 17 may be regarded as interconnecting the decorative elements in vertical columns with the number of columns increasing as the lacing progresses. In either case, each lacing, tape or flexible member 17 passes through alined or registering ears 15 in a row and in the columns or superposed rows. Hence there is a high degree of flexibility in the handbag so that it may expand in width to accommodate its contents. Such expansion or outward bowing or convexing of the side walls in a horizontal direction occurs by pivotal movements between the decorative elements at the ears 15, about the lacing 17. No twisting of the latter occurs, nor does the lacing exercise any restraint upon this free movement of the elements, thus affording an essential requisite of any good handbag—ample flexibility to suit the contents. The utility of this feature is of particular advantage at the vertical ends 18 of the handbag, as shown in Fig. 3. This result is greatly facilitated because the center lines of the ears lie at the rear position of the decorative elements. It is at these ends that the relative angular movement is at a maximum, and yet the contour of the handbag is maintained and there is no distortion between the side walls, a result not heretofore possible.

In course of the relative angular movements of the decorative elements 11 in parallelism to the lacing 17, the free edges 14 of each element slidingly abuts ears 15 of adjacent elements. And because one of the ears 15 is at an upper part and the other at a lower part of the element, the latter is held in its field so that protrusion cannot occur as in the case of placing both ears at an upper or at a lower part of the element. By reason of the columns of ears or tubes 15, each ear or tube is retained in its field at both ends, and all of them mutually contribute to the production of a uniform field, which is constantly so maintained.

The handbag walls also possess flexibility in a direction transverse to the lacing, because the latter consists of pliable material. The flat face

abutment between the ears 15 tends to diminish this flexibility, but the ears may be relatively small in diameter and may be beveled at their ends as in Fig. 8, or may be reduced in length so as to be spaced from the edges 16. The relatively high sections 12a of the elements are beveled at 12b so that the edges 16 afford mutual pivotal abutment. The flexibility transverse to the lacing is of relatively lesser importance. It is preferred to maintain the uniformity of the ears 15, thus permitting the use of a simpler die, and wholly covering the lacing against soiling and wear. And the high portions 12a protect the ears 15 from breakage or chipping at their ends.

In a handbag, the lacing extends continuously along the side walls and around the bottom of the bag, being anchored in place at the mouth of the bag, in any suitable manner well known in the art. The lace at each end of the handbag may be arranged as a loop, one section passing through the ears and the other brought into the bag and anchored at the bottom, or at the mouth of the bag, with the other section. A lining may cover and conceal the connections for the lacing, or the latter may be anchored to the lining or to reinforced or stiffened parts thereof at the mouth of the bag, all of which expedients are well known in the art and hence are not shown herein. For the present invention it suffices that the lacing is suitably anchored at its ends and is otherwise free. This is different from those cases in which lacing is stitched or tacked to a backing or lining at each horizontal row or course. Such a multiplicity of connections is here unnecessary because of the improvements afforded by this invention.

It will now be apparent that lacing in only one direction fully interconnects a field of decorative elements in rows and columns, without intermediate connections or anchorages for the lacing, and by the use of identical decorative elements throughout. The significance of the last named feature will be best appreciated on considering that if interfitted T-shaped elements, for instance, are employed, certain elements will have to be L-shaped in order to obtain a uniform or rectangular field of elements, and the assembling and lacing of such a field is obviously more laborious.

In assembling a field of decorative elements 11, a field thereof are assembled on a suitable platen or holder, and the lacing is then readily strung through, with or without a needle, since the alined ears form virtually continuous, smooth walled tubes. In making a handbag, the laced field may be folded in half, causing the ears at the ends 18 to interfit, after which lacing is strung through those ears. Now the lacing ends are anchored in concealed position, completing the outer wall structure. Then a lining may be inserted, and a slide fastener applied thereto.

In Fig. 8 is shown a modified decorative element 20 which differs from that at 11 in that the tubes or ears 15a are arranged so as to prevent the lacing from projecting at the top and bottom of the handbag as shown in Figs. 1 and 2. For this purpose the inner portions of the ears are beveled, recessed or cut away at the upper and lower edges of each element as shown at 21, the lacing 17a being laterally or rearwardly extended through these openings to illustrate what would happen at the top and bottom of the handbag. It is now seen that while the lacing would be exposed, it is set in so as not to be subjected to wear and abrasion.

To increase the flexibility of the handbag transversely to the lacing the ears 15a are beveled at

their outer ends at the front of the element as shown at 22. The bevels cooperate with the recesses 21 to reduce the abutting surfaces between registering ears so that the elements can freely pivot relatively to each other along the lines 16 which lie in a plane central to the ears.

I claim:

1. A handbag having a field of decorative elements in rows and columns, each element having a decorative body portion and ears laterally projecting therefrom, the ears of adjacent elements being offset relatively to each other and aligned with each other, and lacing strung through the aligned ears to interconnect the decorative elements in rows and columns.

2. A handbag having a field of decorative elements in rows and columns, each element having a decorative main body section and ears laterally projecting therefrom, the ears lying at the rear portions of the body sections and the latter projecting forward of the ears, and lacing interconnecting the ears in rows and columns.

3. A handbag having a field of decorative elements arranged in rows and columns and being in contact with each other, each decorative element having a decorative body section and ears disposed solely at two opposite edges thereof, the remaining edges being free, the ears of one decorative element being offset relatively to the ears of adjoining elements and interfitted in alignment therewith so that the ears lie wholly in said rows, the ears lying in the plane of the rear portion of decorative body section and the latter projecting forwardly of the ears, the ears in different rows being in alignment with each other, and lacing strung through the aligned ears to interconnect the elements in each row and to interconnect the elements in columns, said lacing extending along said columns.

4. A fabric including a series of decorative elements each having two ears, said ears being located at opposite ends of the elements, the length of an ear being not more than half the width of its element, the elements lying in rows with the ears of one element contacting adjacent edges of an adjoining element, said rows being free of lateral projections, with the side edges of each element continuously contacting side edges of adjoining elements, and flexible lacing extending only transversely of the rows through the ears whereby the elements of each row are articulated together, the lacing forming flexible connections between the rows at the ears.

5. A fabric including a series of decorative elements each having a generally rectangular plate-like portion and ears connected thereto at opposed, vertical edges of the said plate-like portion, the remaining, horizontal edges being free of the ears, the length of each ear being not more than one-half of the vertical width of its element so that at least one-half of each of said vertical edges is free of its ears, the elements being interfitted in rows and columns with the ears in register with each other along the columns and the free horizontal edges of the elements lying along the rows with those of one row movably contacting those of an adjacent row, and the ear of one element contacting a free vertical edge of an adjacent element, and flexible lacing strung through the ears and being the sole means for interconnecting the elements in said rows and columns.

6. A flexible fabric including a series of decorative elements arranged in contact with each other in rows and columns, each element having a plate portion providing the edges for said contact, the

edges lying in a plane, and ears on the elements at opposite edges thereof, forming rows of ears, the ears of adjoining elements in each row being in register with each other and the ears in one row being in register with the ears in adjoining rows, the center lines of the ears lying in said plane so that portions of the ears lie below their plate portions, and flexible members extending through the ears for interconnecting the elements in said rows and columns.

7. A flexible fabric comprising a series of decorative elements each having a generally rectangular plate-like portion, ears at opposite ends of plate-like portion not more than one-half the width of the latter, said ears terminating at diagonally opposite corners of the plate-like portion, the elements being interfitted in rows with the ears of adjacent elements in register with each other, and the rows lying in uniform edge to edge contact with adjacent rows with the ears of the different rows in register with each other, and flexible members extending through the ears to interconnect the elements in rows and columns.

8. A handbag having a flexible side wall comprising a field of decorative elements in rows and columns and in contact with each other along said rows and columns, said elements having ears in each row offset so that the ears of adjacent elements register with each other, the ears of the different rows being in register with each other, each element having certain edges on all four sides thereof in contact with adjacent elements, said edges lying in a plane at the base of each element, said ears having their center lines in said plane, and flexible lacing extending through the ears transversely of the rows of interconnecting the elements in rows and columns.

9. A handbag having flexible side walls each comprising a field of decorative elements disposed in rows and columns in contact with each other, each element having ears disposed solely at two opposite edges, the ears of adjacent elements being interfitted so that the ears of each element are in register with the ears of elements at said opposite edges, in each field and at the junction of the side walls at an edge of the handbag, the ears in a row registering with ears in adjacent rows in each field and at the apex of the junction of the side walls, flexible members extending transversely of the rows through said ears and constituting the sole means interconnecting said elements in rows and columns, said flexible members permitting flexure of the side walls transversely of said members and the elements being adapted to pivot relatively to each other about said members and the side walls being pivotally related to each other about the lacing member in the ears at said apex.

10. A flexible wall comprising a field of elements, each element having a generally rectangular decorative portion, the decorative portions lying in edge to edge contact with each other in columns, the decorative portions also lying in spaced relation to each other in rows, a pair of registering tubes between each pair of decorative portions in said rows, one tube being integral with one decorative portion and the other tube being integral with the other decorative portion, the length of said pair of tubes being approximately equal to the width of a row, the tubes of each row being in register with the tubes of adjacent rows, whereby the tubes form substantially continuous tubes approximately equal to the length of said columns, and flexible lacing in said substantially continuous tubes interconnect-

ing the decorative elements to maintain said field.

11. A flexible wall according to claim 10 where-
in the tubes of each element are located adjacent
to diagonally opposite corners thereof, whereby
the element is retained against protruding from
the field.

12. A flexible wall according to claim 10 where-
in the tubes of each element are provided with
cut-outs at their outer ends at the rear of the
element to accommodate end portions of the lac-
ing.

13. A flexible wall according to claim 10 where-
in the center lines of the tubes lie in the plane
of the rear surfaces of the decorative portions.

14. A flexible wall according to claim 10 where-
in

5 in the center lines of the tubes lie in the plane of
the rear portions of the elements, the tubes hav-
ing cut-outs at their outer ends at the rear of
the decorative elements, said tubes having bevels
at their outer ends at the front of the decorative
elements.

15. A device including a field of thin edge dec-
orative plate elements lying edge to edge and
having registering ears whose center lines lie
parallel to the plane of the plate elements, flex-
ible lacing through the ears, the latter being so
positioned at edges of the elements as to consti-
tute abutments to prevent the elements from par-
tially telescoping each other.

VICTOR BERKOWITZ.
